CHARLES H. CHAPMAN, OF WINCHESTER, MASSACHUSETTS; FRANK F. B. CHAPMAN
ADMINISTRATOR OF SAID CHARLES H. CHAPMAN, DECEASED.

BALL-BEARING.

1,213,805.

Specification of Letters Patent.

Patented Jan. 23, 1917.

Application filed January 23, 1914. Serial No. 813,971.

To all whom it may concern:

Be it known that I, CHARLES H. CHAPMAN, a citizen of the United States, residing at Winchester, in the county of Middlesex 5 and State of Massachusetts, have invented a certain new and useful Improvement in Ball-Bearings, of which the following is a full, clear, and exact description.

The object of this invention is to provide 10 an improved ball bearing for shafting of simple construction and few parts which is supported in hangers and the like, whereby the entire bearing may be applied to or disconnected from the shaft and hanger without disconnecting or disturbing either the 15 pulleys or shafting.

The invention consists of a ball bearing, especially adapted for shafting, in accordance with the stated object of the invention, 20 and comprises a divided sleeve having its ends constructed so as to be fitted to the shaft and formed with ball races, and divided rings adapted to be applied to the sleeve so as to hold the parts of the sleeve 25 together and fixedly lock them to the shaft and also adapted to be operated to permit the removal of the sleeve from the shaft, as hereinafter explained and claimed.

The invention also consists of certain 30 details of construction, as hereinafter more fully explained and claimed.

In the accompanying drawings illustrating the invention, in the several figures of which like parts are similarly designated, 35 Figure 1 is a side elevation of the bearing with one end partly in section to show the interior construction, which is similar in both ends of the bearing, a part of the hanger being shown in section. Fig. 2 is an 40 end elevation of Fig. 1, looking at the sectioned end and showing a modification of the hanger arrangement. Fig. 3 is a perspective view of the locking ring which locks the parts of the sleeve together and firmly 45 to the shaft. Fig. 4 is an interior elevation of the upper part of the housing. Fig. 5 is an interior elevation of one part of the sleeve. Fig. 6 is a side view of the other part, and Fig. 7 is an end elevation thereof. 50 Fig. 8 is an elevation of the ball retainer partly in longitudinal section, and showing the sleeve and shaft in cross-section. Fig. 9 is a cross-section of the ball retainer taken on line A B, of Fig. 8.

55 The part numbered 1 may be a shaft, which, for purposes of illustration of the

invention, is shown as to be supported in ordinary hangers, such as 2. At the point of application to the hanger the shaft is embraced by a divided sleeve 3, composed, for example, of halves of identical construction, excepting that one half may have a number of pins 4 which enter corresponding holes 5 in the other half so as to aline them about the shaft. These halves are secured about 60 the shaft by means of screwthreaded locking rings 6 engaging screwthreads on the tapered compressible ends 7 of said halves, and these ends may be rendered compressible by means of longitudinal slits 8 and cut 65 away portions 9 on their ends next to their meeting edges. The locking rings may be made in halves hinged together as at 10, and adapted to be separably united by a screw 11, so that they may be readily applied and removed without dismounting the 70 shaft. These rings may have the nicks 12 to receive a spanner wrench to tighten their hold on the sleeve when in place and to run them off so as to facilitate their separation. 75 The sleeve ends are of smaller internal diameter than their middle portions. Next to their ends the sleeve is constructed with circumferential grooves 13 forming ball races and the interior diameter of the 80 sleeve under these ball races is about the same as at the ends so as to seat on the shaft and thereby resist deformation under excessive loads. The housing 14 is likewise divided, and made in halves, one of which is 85 shown in Fig. 4, and these halves may be identical, excepting that one has the pins 15 and the other holes 16 entered by the pins to aline the halves about the sleeve, and the 90 uppermost half has the ducts 17 for the introduction of lubricant. These ducts may be closed by pins 18 so constructed as to be used also for forcing the lubricant into the 95 bearing. The ends of the housing halves are formed preferably with chilled ball 100 races 19 to correspond and aline with the ball races on the sleeve, and the radii of these ball races are slightly larger than the radius of the load-carrying balls, and this variation is regulated so as to give the desired width 105 of contact of the balls on the races. The ball races on the sleeve and the housing are preferably cast upon chills, to render them very smooth and hard, and so as to require 110 comparatively little grinding. The housing halves are provided with opposite alined exterior bosses 20 to coöperate with supports

21 applied to the hanger 2. As shown in Fig. 1, these bosses are spherical and the supports 21 are cup-shaped to fit them. As shown in Fig. 2 the supports 22 may be 5 cones to enter corresponding cavities 23 in the bosses. In either case the supports are provided with screwthreaded shanks 24 so that the supports may be adjusted in the hangers into proper bearing-sustaining relation to the bosses and fixed in such adjusted 10 position by the lock-nuts or jamb-nuts 25.

In the form shown in Fig. 1, the construction is substantially a ball and socket joint, and the bearing automatically alines itself 15 both vertically and laterally with the shaft when the hanger is properly set, but with the construction shown in Fig. 2, the bearing can swing horizontally to aline itself with the shaft, but can not swing vertically excepting to a very slight extent if at all, dependent upon the fit of the pointed screw supports in the cavities in the bearing bosses.

The ball races may be such as to receive 25 any desired arrangement of bearing balls, but I prefer to use an arrangement comprising load-carrying balls 26 with alternating idler balls 27 of smaller diameter collocated in an annular retainer 28 which is provided 30 with holes 29 to receive the load-carrying balls and intermediate grooves 30 to hold the idler balls against outward escape. This ball retainer is of slightly smaller diameter than the outside diameter of the ball race, 35 so that in coöperation with the load-carrying balls it will be held in concentric position in the ball race and rotate therein. The ball race in the sleeve prevents the escape of the idler balls in that direction, and 40 these balls are thrown out by centrifugal force into the groove 30 in the operation of the bearing and held at or near the center line through the load-carrying balls. When the bearing is at rest, the uppermost idler 45 balls may drop down upon the chilled races of the sleeve, but as soon as the bearing is set in operation the centrifugal force acts upon these balls and at once causes them to assume their position in the grooves 30 centrally between the load-carrying balls.

As shown in Figs. 1 and 9, the ball retainer may be made in two or more parts interlocked together, as by the L-shaped joints 31.

55 In applying the bearing to a shaft, the lower half of the housing is placed in the hanger, and then the two halves of the sleeve are applied to the shaft, and the opened locking rings are placed around the shaft, 60 and then closed, and the rings screwed up upon the threaded portions of the sleeve until the sleeve fits the shaft with an easy slip fit. The retainers and balls are then

placed around the ball races of the sleeve, and then the upper portion of the housing 65 is applied, and forced down into place by turning the upper screw support in the hanger. The lubricating holes are filled with grease and the pins replaced therein so as to force the grease down into the bearing and into position to be distributed by the ball retainers, after which the locking rings are tightened so as to firmly lock the ends of the sleeve to the shaft and cause the sleeve to rotate with the shaft and prevent 70 lateral movement of the sleeve upon the shaft.

75 By means of the invention herein explained, I am able to produce a bearing simple in construction and of few parts at 80 a cost considerably below the cost of a bearing made with independent or continuous ball cups and cones, which are very expensive and hard to install, requiring the uncoupling of the shaft and the removal of 85 pulleys, both for the installation of the bearing and its removal.

Obviously variations in details of construction are within the principle of the invention and the scope of the claims herein. 90

What I claim is:—

1. In a ball bearing for shafting, a divided sleeve provided with slotted and tapered screwthreaded ends adapted to be fitted to the shaft and having circumferential 95 chilled ball-races formed thereon, and divided and hinged locking rings having tapered screwthreaded portions to engage the threaded tapered ends of the sleeve and adapted to hold the parts of the sleeve together and fixedly lock the sleeve to the shaft, said locking rings adapted to be opened and removed from the sleeve to permit the removal of the sleeve and its ball-races from the shaft. 100

105 2. In a ball bearing for shafting, a divided sleeve having tapered ends of less interior diameter than the remainder of the interior of the sleeve and circumferential chilled ball-races formed thereon and adapted to be fitted to the shaft, means to removably bind said sleeve at its ends to the shaft, a divided housing having interior chilled ball-races formed therein in alinement with the ball-races of the sleeve and applied to 110 said sleeve, and bearing balls arranged in the alined ball races of the sleeve and housing.

115 In testimony whereof I have hereunto set my hand this 21st day of January A. D. 120 1914.

CHARLES H. CHAPMAN.
